UNITED STATES PATENT OFFICE.

LLOYD G. COPEMAN, OF FLINT, MICHIGAN.

REFRIGERATOR CONSTRUCTION.

Application filed February 2, 1924. Serial No. 690,143.

To all whom it may concern:

Be it known that I, LLOYD G. COPEMAN, a citizen of the United States, residing at Flint, in the county of Genesee and State of Michigan, have invented certain new and useful Improvements in Refrigerator Constructions, of which the following is a specification.

This invention relates to refrigerator construction, particularly that class of refrigerators in which the outer and the inner shells are formed of cast stone work suitably insulated from one another. This invention pertains more in detail to the insulating medium between the inner and outer shells of a cast stone refrigerator.

In refrigerators of this character it has been customary to fill the space between the inner and outer shells with a suitable insulating material such as mineral wool or ground cork, but it has been found that this insulating medium will not strengthen the refrigerator as a whole. If the refrigerator should fall or be struck at one of the corners, the shell of the refrigerator might crack and be seriously damaged. To overcome this likelihood of the refrigerator becoming damaged, I provide an insulating medium that is cast into the refrigerator, the form of insulating medium that I use being known as an insulating cement. This cement, although not positively uniting with the cast inner and outer shells, necessarily sticks pretty hard to the two shells and acts as a solid reinforcing filler to bind the outer and inner shells together.

In this invention the insulating cement is poured in all the spaces between the different compartments, and as it hardens it tends to hold the refrigerator together as a compact unit. In case of severe strains, the whole refrigerator unit must give way before a severe strain can be brought on any one part. This insulating cement has no great tensile strength but when set is very hard and able to resist severe compression strains.

Fig. 1 is a vertical sectional view through a cast stone refrigerator constructed in accordance with my invention.

Fig. 2 is a horizontal sectional view taken on the line 2—2 of Fig. 1.

Fig. 3 is a horizontal sectional detail of a modified form of construction in which the insulating layer of cork board is omitted.

Fig. 4 is a similar detail showing another

modified form of construction in which the outer shell is formed with a cast stone front.

Fig. 5 is a detail showing how this form of insulating medium could be applied to a cast refrigerator door.

a designates the outer shell of a cast stone refrigerator; *b* designates the inner shell and *c* designates the ice tank. The inner shell, shown in the drawings, is one in which the food chambers are cast in a shape approximating the letter L, thereby leaving a space in the upper left hand corner for receiving the ice tank which is here shown formed of sheet metal. However, the inner shell could be cast so as to include the ice tank or the ice tank could be separately formed of stone work.

The form of refrigerator shown in the drawings is provided with a wood front *d*. This form of construction is shown and claimed in my pending application Serial No. 686,882 and the details of construction need not be here described. However, the inner shell abuts against the wood front carried by the outer shell and is supported therefrom by suitable angle irons as shown in my previous application. A back plate *e* is fitted in the open end of the outer shell and when fastened to the inner shell will securely hold the two shells in place and prevent relative movement between the two.

The space between the cast inner shell and the cast outer shell is filled with an insulating cement designated *f*, while the same is wet. This plastic insulation may easily be poured while wet and is very light and hard when it dries and becomes a good insulator preventing the conductivity of heat from the exterior of the refrigerator to the interior. I preferably form this mixture of 30% magnesium oxide, 15% cork dust, 5% ground cork, 5% silocel or kieselguhr (wet) and the balance or 45% of magnesium chloride which has a specific gravity in this particular mixture of 22 degrees Baumé. However, this mixture may be varied to some extent such as the replacing of the cork dust, ground cork and silocel with glue and wood flour, or glue and ground cork, or glue and sawdust, or other combinations which will be satisfactory for this purpose. The idea, is, to pour cement into the space between the shells, which when dried becomes very hard and strong, and is a good heat insulator.

In order to be doubly sure that the inner shell is thoroughly insulated from the outer shell, I line the inside of the outer shell with a $\frac{7}{8}$ " cork board *g*. This corkboard simply lies against the inside of the outer shell, and the cement as it hardens, expands slightly and presses this corkboard *g* tightly against the outer shell *a* thus the entire refrigerator is practically a solid cast stone work. The 10 inner and outer shells are first cast and allowed to set and then assembled together, the corkboard is then pressed in position, and next the insulating cement is poured in the spaces between the two shells and allowed to set. This cement when dried has the property of resisting compression strains and serves to bind the outer and inner shells together.

However, this insulating cement is a good 20 nonconductor of heat and it is possible to construct the refrigerator without the use of this corkboard as shown in Fig. 3. This corkboard is merely used to make doubly sure that the heat conductivity is broken.

25 In Fig. 4 I have shown a detail of a refrigerator construction in accordance with the disclosure in my pending application Ser. No. 686,883 which shows a cast stone refrigerator front with suitable insulating 30 frames against which the inner shell abuts. This form of insulating the inner and outer shells is clearly adaptable to this form of construction as well as to the wooden front construction. Fig. 5 shows a detail of a 35 refrigerator door having a wooden panel with a cast stone back united thereto. This shows how this form of insulating medium can be cast into the space between the back and front of the door for insulating the same. The use of such an insulating cement 40 in door construction would probably be better adapted for use when the front and back of the door are both made of cast stone work.

45 This insulating cement is applicable to refrigerators having an outer shell made entirely of wood, and an inner shell of cast stone or of sheet metal. This construction eliminates expensive bracing and supports 50 for screwing the inner shell to the outer shell, besides serving to thoroughly insulate the two shells.

What I claim is:

1. In a refrigerator construction, the combination of a moulded outer shell and a moulded inner shell secured together in spaced relation, and an insulating cement between said shells serving to bind them together and highly resistant to compression strains to form an entire moulded structure.
2. In a refrigerator construction, the combination of a cast stone outer shell and a cast stone inner shell secured together in spaced relation, and an insulating medium 60 lying between said shells serving to bind

them together and highly resistant to compression strains to form a solid moulded stone structure.

3. In a refrigerator construction, the combination of a cast stone outer shell and a cast stone inner shell secured together in spaced relation, and an insulating cement poured between said shells and allowed to expand on setting to bind the two shells together. 75

4. In a refrigerator construction, the combination of an outer and an inner shell secured together in spaced relation, and an insulating cement poured therebetween in a semi-fluid condition and including cork dust and a cementitious material, which when allowed to set will expand and bind the two shells together. 80

5. In a refrigerator construction, the combination of an outer shell and an inner shell secured together in spaced relation, and an insulating cement lying therebetween and including cork dust, ground cork and a cementitious material. 85

6. In a refrigerator construction, the combination of an outer shell and an inner shell secured together in spaced relation, and an insulating cement therebetween and including cork dust, ground cork, kieselguhr and a cementitious material. 90

7. In a refrigerator construction, the combination of an outer shell and an inner shell secured together in spaced relation, and an insulating cement therebetween comprising cork dust, ground cork, kieselguhr, magnesium oxide and a cementitious material. 100

8. In a refrigerator construction, the combination of an outer shell and an inner shell secured together in spaced relation, an insulating cement therebetween comprising cork dust, ground cork, kieselguhr, magnesium oxide and magnesium chloride. 105

9. In a refrigerator construction, the combination of an outer moulded shell and an inner moulded shell secured together in spaced relation, and an insulating cement cast between said shells whereupon the whole refrigerator is bound together and becomes a solid moulded structure highly resistant to compression strains. 110

10. In a refrigerator construction, the combination of an outer shell and an inner shell secured together in spaced relation, an insulating board in said space and an insulating medium between the insulating board and the shells and highly resistant to compression strains. 120

11. In a refrigerator construction, the combination of a cast stone outer shell and a cast stone inner shell secured together in spaced relation, an insulating board in said space, and an insulating medium between the board and the shells and highly resistant to compression strains. 125

12. In a refrigerator construction, the

combination of an outer shell and an inner shell secured together in spaced relation, an insulating board in said space, and an insulating cement cast between the shells and highly resistant to compression strains, said cement becoming hardened and expanded when set to bind the two shells together.

13. In a refrigerator construction, the combination of an outer shell and an inner shell secured together in spaced relation, a cork board lining for the inside wall of the outer shell, and an insulating cement between the cork board and the inner shell to bind the same together.

14. In a refrigerator construction, the combination of an outer shell and an inner shell secured together in spaced relation, an insulating board lining for the inside wall of the outer shell, and an insulating cement poured into the space between the board and the inner shell whereby when dried the said insulating cement is expanded and hardened for the purpose of binding the inner shell and outer shell together to reinforce the refrigerator.

In testimony whereof I affix my signature.

LLOYD G. COPEMAN.
